FIG. 3.

or - Hazard E. Miller
ATTORNEY.

UNITED STATES PATENT OFFICE.

ALBERT R. LONG, OF LOS ANGELES, CALIFORNIA.

FUEL-HEATER.

1,263,259.

Specification of Letters Patent. Patented Apr. 16, 1918.

Application filed January 4, 1917. Serial No. 140,544.

To all whom it may concern:

Be it known that I, ALBERT R. LONG, a citizen of the United States, residing at Los Angeles, in the county of Los Angeles and 5 State of California, have invented new and useful Improvements in Fuel-Heaters, of which the following is a specification.

My object is to improve the lay-out and details of construction of a fuel heater for 10 internal combustion engines and especially for automobile engines:

The invention is illustrated, by way of example, in the accompanying drawings in which:

15 Figure 1 is a view in side elevation illustrating the forward end of an automobile and disclosing it with a portion of its hood broken away to show the intake and exhaust manifolds of the engine and the application 20 of the heater thereto.

Fig. 2 is an enlarged view in side elevation illustrating the heater and its features of construction.

Fig. 3 is a view in vertical section as seen 25 on the line 3—3 of Fig. 2 and particularly illustrates the manner in which the heater is positioned upon the manifold and secured in a leak-proof manner.

Referring more particularly to the drawings, 30 10 indicates an internal combustion engine which is provided with an intake manifold 11 and an exhaust manifold 12. As illustrated in the drawings, these manifolds are positioned upon the same side of the 35 engine, although this is not a necessary feature of construction. The intake manifold is fitted with a carbureter 13 through which a gaseous fuel is led to the engine cylinders. In order to heat this fuel, the intake manifold 40 is partially inclosed within a jacket or heater which is supplied with hot exhaust gas from the exhaust manifold, after which the gas is permitted to pass from the heater and to exhaust at a suitable point beneath 45 the car.

The heater is composed of a front jacket member 14 and a rear jacket member 15. These members are adapted to be secured together by bolts 16, 17 and 18 and when 50 thus secured form a heat chamber 19 through which a portion of the intake manifold extends. The manifold shown in the drawings is of T-shape and the jacket provided for it 55 partially incloses the head of the manifold and extends downwardly in a manner to

partially inclose the vertical extension of the manifold as it leads to the carbureter. The upper portion of the jacket members do not entirely encompass the head of the manifold but pass partially around it, as illustrated 60 in Fig. 3. A pair of ears 20 and 21 are formed upon the jacket member 14 and pass partially around the top of the manifold in a manner to more securely grip it. The inner face of the entire marginal edge of each 65 of the jacket members 14 and 15 are formed with packing grooves 22 and 23 within which suitable asbestos packing is placed to prevent leakage of the gas from the chamber 19. 70

The chamber 19 is supplied with exhaust gas from the manifold 12 through a vertically extending connecting pipe 24. This pipe is substantially U-shaped and one of its ends connects with an opening 25 in the exhaust manifold. The other end passes into a screw-plug 26 which is threaded into an opening 27 in the face of the jacket plate 14. It will thus be seen that as the burnt gases 80 pass through the exhaust manifold, a portion of them will pass downwardly through the pipe 24 and into the heating compartment 19. While in this compartment it will completely surround the intake manifold and raise it to a high temperature. After 85 the gas from the exhaust manifold has circulated through the compartment 19, it will pass outwardly through a conduit 28 and will be thereby led to a suitable point of exhaust. 90

In operation, the two parts of the jacket are first positioned around the intake manifold, as disclosed in the drawings, after which an opening is made through the side wall of the exhaust manifold and in convenient relation to the opening 27 in the jacket 14. The connecting pipe 24 is then properly positioned in relation to the two openings so that burnt gas will flow into the chamber 19 around the intake manifold. 100 The intake gas passing upwardly from the carbureter will be heated thereby and will pass into the cylinders in a more perfect form of gas than were the passage-ways cold. The exhaust gas will then pass through 105 the pipe 28 and away.

It will thus be seen that the apparatus here provided for heating the intake gas to be delivered to an engine cylinder is simple in its construction, of few parts, and may be 110

readily applied without the services of skilled mechanics.

I claim:

- The combination with an intake manifold, 5 of a fuel heater comprising a front jacket member and a rear jacket member; the upper edges of the jacket members pressing against opposite sides of the head of the manifold and corresponding side edges 10 pressing against opposite sides of the vertical extension of the manifold and the remaining marginal edges of the jacket mem-
- bers meeting; a U-shaped pipe mounted with one end tapped into the exhaust manifold and the other end tapped through the front 15 jacket member, packing between the marginal edges of the jacket members, and bolts through the marginal edges of the jacket members for connecting the jacket members rigidly together and tightly against the 20 manifold.

In testimony whereof I have signed my name to this specification.

ALBERT R. LONG.
